UNITED STATES PATENT OFFICE.

GEORGE EDWIN JONES, OF CHICAGO, ILLINOIS.

REFRIGERATING DEVICE.

1,017,217.

Specification of Letters Patent.

Patented Feb. 13, 1912.

Application filed October 12, 1911. Serial No. 654,290.

2. *all whom it may concern:*

Be it known that I, GEORGE EDWIN JONES, a citizen of the United States, residing at Chicago, in the county of Cook and State of Illinois, have invented certain new and useful Improvements in Refrigerating Devices, of which the following is a specification.

My invention relates to refrigerating or chilling devices and has particular reference 10 to a device adapted for refrigeration by evaporation.

It is a well known scientific fact that heat units may be subtracted from a body by evaporation of a liquid and that the extent 15 of subtraction of such units is proportionate to the speed of evaporation. The heat which thus disappears by virtue of the passage of the liquid into a gaseous condition is called the latent heat of evaporation. By the use 20 of an exceedingly volatile liquid an extreme cold may be produced. However, the present invention relates to a device for use with ordinary water by reason of which articles may be chilled and retained in such condition 25 indefinitely, the only requirement being that the water is kept supplied to the walls of the container.

I am aware that it is not broadly new to provide a device similar to that herein shown 30 and described and having many of the properties thereof. However, in the devices heretofore suggested, it has been necessary to supply the liquid to the walls of the container by immersing the container as a 35 whole, or in some other equally inconvenient manner. Furthermore, the water thus applied would very shortly evaporate making necessary further applications thereto. I have therefore devised a refrigerating container 40 so arranged that a sufficient amount of water may be applied to maintain the walls in saturate condition for a much longer time than has heretofore been possible.

45 My invention will be more readily understood by reference to the accompanying drawings, wherein,

Figure 1 is a side elevation of a container such as contemplated by me, and Fig. 2 is a 50 vertical section through the container shown in Fig. 1.

Referring more particularly to the drawings it will be seen that my container is preferably oval in cross-sectional outline, and 55 comprises a lower or base portion 10, having an outstanding flange 11, on which the con-

tainer may be rested. The upper edge of this half terminates in a trough 12 and an upstanding peripheral rib 13. In order to direct the liquid to the inner and outer portions of the wall and thoroughly distribute the same, I provide within the trough 12, a plurality of staggered depressions 14, 15. It will be seen that the depressions 15 direct the water to the outside portion of the walls 65 and the holes 14 to the inside. I contemplate providing a large number of these holes around the upper edge of the lower container and by this means provide a receptacle for liquid which will not be taken 70 up by the walls of a container. It will be understood that direct evaporation of the liquid is proportional to its area of exposure to the atmosphere. Therefore by providing these depressions I reduce the 75 area of exposure to the atmosphere and prevent direct evaporation of the liquid, before it can be taken up by the material forming the wall.

It will be understood that the container 80 described is preferably formed of plaster of Paris or some material having such properties, that is, the property of absorbing a large quantity of water and which will not take up odors from the articles carried in 85 the container. The upper half 16 of the container has at its lower extremity an inwardly facing groove 17, adapted to fit over the flange 13, and provide against the shifting of the top. In order to permit of the 90 easy handling of the device and also to provide a further water reservoir, I furnish the upper extremity of the container with a flange 18, forming a trough 19, having similar holes 20, 21, the holes 20 directing wa- 95 ter to the outside portions of the walls and the holes 21 to the inside. In order to prevent the forming of a vacuum within the container and also to permit the escape of heat, I provide perforations 22, through the 100 walls of the upper half.

In operation, the articles to be chilled are placed within the container, the cover or upper half 16 applied, then a quantity of water is poured into the upper and lower 105 troughs and allowed to soak into the walls. As soon as the walls become saturated, water will remain in the troughs and perforations, ready to percolate into the walls as evaporation progresses. In this way it has 110 been found that no attention need be paid to the container for long periods.

It will be obvious than many modifications may be made in the exact structure herein shown and described, all without departing from the spirit of my invention.

5 I claim:

1. A refrigerating device composed of interfitting upper and lower sections, said lower section near its upper extremity being provided with a plurality of staggered holes by means of which water may be directed to the inner or outer portions of the walls therebelow, substantially as described.
- 10 2. A refrigerating device composed of interfitting upper and lower sections, said lower section having an annular flange near its upper extremity, whereby a trough is formed, said flange containing a relatively

large number of staggered holes, whereby water is directed to the inner and outer portions of the walls, substantially as described. 20

3. A refrigerating device composed of interfitting upper and lower sections, said lower section having an annular flange providing a trough, said upper section also having an exterior flange and provided near its 25 top with a plurality of staggered holes, said flange providing a trough and lifting or handling projections, substantially as described.

G. EDWIN JONES.
